UNITED STATES PATENT OFFICE.

CHARLES J. PILLING, OF PHILADELPHIA, PENNSYLVANIA, ASSIGNOR TO HIMSELF AND GEORGE P. PILLING, (COPARTNERS TRADING AS GEORGE P. PILLING & SON,) OF SAME PLACE.

VAGINAL SPECULUM.

SPECIFICATION forming part of Letters Patent No. 672,239, dated April 16, 1901.

Application filed May 21, 1900. Serial No. 17,444. (No model.)

To all whom it may concern:

Be it known that I, CHARLES J. PILLING, a citizen of the United States, residing at the city of Philadelphia, in the State of Pennsylvania, have invented certain new and useful Improvements in Vaginal Speculums, of which the following is a full, clear, and exact description, reference being had to the accompanying drawings, forming a part of this specification.

My invention relates to surgical instruments of the class of bivalvular vaginal speculums.

It has for its object to increase the efficiency of the instrument, effected by the modifications in construction hereinafter described.

In the drawings illustrating my invention, Figure 1 is a side elevation, Fig. 2 a plan view, Fig. 3 a vertical section, and Fig. 4 an end view, of the detached lower member of the instrument.

The general form of the device in respect of having a lower blade or member A with a downwardly-projecting stem a, on which the 25 adjusting-screw T is mounted, and with ears b b, to which a single upper movable blade or a pair of movable blades B B are hinged at d, said movable blades having operating-arms f f, is old. At the point where the said movable members B are hinged to the ears of the blade A it is preferable to construct the device with a lock or key m, which is in the form of a washer having an open end to enable it to be driven around the projecting end of the 35 pivot-pin, its free end being then let into the operating-arm f of the blade B. Such is the general character of speculums now in use. To remedy certain of its more prominent defects, I give strength and rigidity to and at the same time provide a drainage-channel in the lower fixed blade or member A by extending the concavity of the blade to its downwardly-projecting stem a, so as to form a continuous unbroken concavity narrowing into a 45 groove or gutter in the stem a, open at the end, and I apply the same principle of construction to the upper and movable blade or blades B B, though only for the purpose of securing rigidity, and hence consequent capacity of being made lighter in weight.

Another and equally important novel feature of my invention is the mechanism by which the movable blade or blades are operated. Formerly when the movable blades were raised by turning the thumb-piece s on the screw T they could only be restored to normal position by manually pushing them down, and frequently the blades (in a trivalvular speculum with divided or double upper blades) would not be operated uniformly. 55 In my device I operate the upper movable blade (or divided blade in a trivalvular device) positively in both directions. One end of the screw T is fixedly mounted in the end of the stem of the blade A, projecting rearwardly, and on the free end of said screw T I provide an annularly-grooved collar S with a thumb-piece s, the collar being centrally recessed and screw-threaded to reciprocate on the operating-screw T of the instrument. The 60 free ends of the operating-arms f f of the movable blade or blades B B rest in the annular groove of the collar S. Hence a turning of the latter by its thumb-piece in either direction will respectively raise and lower the movable 65 blade or blades B B and will effect that operation with perfect uniformity as to both blades, if a divided blade is employed, and in both directions by positive action in either a bivalvular or a trivalvular speculum. 70

Having thus described my invention, I claim as new—

1. In a speculum, the combination with a lower and fixed member, composed of an integral blade and downwardly-extending supporting-stem, substantially at right angles to each other, and formed with a continuous concavity, of a movable upper member pivotally mounted upon said lower and fixed member and having an operating-arm, a rearwardly-projecting screw fixedly mounted on the supporting-stem of the lower member, and an annularly-grooved screw-collar thereon, into the groove of which collar the end of said operating-arm projects, substantially as described. 85

2. In a speculum the combination with a lower or fixed member composed of blade A, stem a, with ears b b, of a pair of movable upper members each having an operating-arm 90

f pivotally connected to one of said ears *b b*, a rearwardly-projecting fixed screw *T* mounted upon the stem *a*, an annularly-grooved screw-collar *S* with thumb-piece *s*, the free ends of the operating-arms *f* projecting into the groove of the collar: substantially as described.

3. In a speculum, the combination with a lower member composed of a blade having a downwardly-extending supporting-stem substantially at right angles thereto, said lower member formed with a continuous concavity, a rearwardly-projecting screw fixedly mounted on the supporting-stem of the lower member, and an annularly-grooved screw-collar thereon adapted to receive the operating-arm of a pivotally-mounted upper member.

4. In a speculum, the combination with the lower member composed of a blade having a downwardly-extending supporting-stem substantially at right angles thereto, a rearwardly-projecting screw fixedly mounted on the supporting-stem of the lower member, and an annularly-grooved screw-collar thereon adapted to receive the operating-arm of a pivotally-mounted upper member.

In testimony whereof I have hereunto affixed my signature this 17th day of May, A. D. 1900.

CHARLES J. PILLING.
